CLAIM

The ornamental design for a baby monitoring apparatus as shown and described.

DESCRIPTION

1. Baby monitoring apparatus

1.1: Perspective

1.2: Perspective

1.3: Front

1.4: Back

1.5: Left

1.6: Right

1.7: Top

1.8: Bottom

The broken lines shown in the drawings are included for the purpose of illustrating portions of the baby monitoring apparatus that form no part of the claimed design.
